UNITED STATES PATENT OFFICE.

EARL THOMPSON, OF NEW YORK, N. Y.

CHAIR SEAT.

Application filed March 17, 1922. Serial No. 544,407.

To all whom it may concern:

Be it known that I, EARL THOMPSON, a citizen of the United States, and resident of the city of New York, in the county of New York and State of New York, have invented certain new and useful Chair Seats, of which the following is a specification.

My invention relates to a new and useful improvement in chair seats.

10 An object of my invention is to provide a chair seat which is an intaglio of the human buttocks in the sitting position distributing comfortably the weight of the body; another object of my invention is to

15 provide a chair seat which will induce correct posture and tend to avoid and prevent mal-position and to correct bad postural habits and another object of my invention is to provide a comfortable and convenient chair

20 seat.

Many anatomical defects, among the more prominent of which are round shoulders, obliteration of the normal lumbar curve, lateral curvature of the spine, sunken chest, 25 prominent abdomen, inequality in the level of the shoulders and other defects with the attendant traumatic conditions result from incorrect sitting posture, and an object of my invention is to correct and overcome this

30 condition.

I accomplish the above objects by the device illustrated in the accompanying drawings, in which—

Figure 1 is a plan view of my improved seat.

Figure 2 is a section on the line 2—2 in Figure 1.

Figure 3 is a section on the line 3—3 in Figure 1.

40 Figure 4 is a section on the line 4—4 in Figure 1.

Similar characters of reference refer to similar parts throughout the several views.

My improved chair seat is preferably 45 formed or constructed of wood or like material and is provided in its upper face with a depressed saucer 1, and outlined posteriorly by a curved margin 3 which corresponds to the posterior of the buttocks of

50 a person seated normally therein.

Two forward shallow flaring channels 4 and 5 are provided, extending from the basin or saucer 1 to the front edge 6 of the seat, to conform to the under muscles of the legs of a person seated thereon, and which are 55 preferably separated by a low ridge 7.

The saucer 1 of the seat is outlined at its front limit by a distinct margin or edge 2 which is not sufficiently high to render it uncomfortable to a person normally seated 60 on the seat but will serve as a deterrent against the occupant sliding forward and assuming an improper position.

The ridge 7 between the forward channels 4 and 5 is extended rearwardly into the basin 65 or saucer 1 in a still lower ridge 8 which disappears rearwardly and merges in the contour of the saucer 1.

In use I prefer to place the seat with a slight inclination depressing the rear at an 70 angle of approximately 3½ degrees from the horizontal.

A person seated in this seat will naturally assume an upright and proper position by reason of the fact that the contour 75 of the saucer 1 will hold the buttocks and tend to prevent careless posture.

Having thus described my invention, what I claim is:

1. In a chair seat, a rearwardly disposed 80 depressed saucer adapted to position an occupant at the rear of the seat and having a front marginal edge extending across the seat intermediate the front and rear edges of the chair seat and two shallow channels 85 extending from the front margin of the saucer to the front edge of the chair seat.

2. In a chair seat, a rearwardly disposed 90 depressed saucer having a curved forward margin adapted to position an occupant at the rear of the seat and two shallow channels extending from the forward margin of said depressed section to the front edge of the seat.

Signed at New York, in the county of 95 New York and State of New York, this 9th day of March, A. D. 1922.

EARL THOMPSON.
